COMBINED POUR SPOUT AND HANGER FOR A CONTAINER

Joseph Marg, 24043 Greenlawn Ave.,
Beachwood, Ohio 44121

Filed Feb. 5, 1969, Ser. No. 15,640

Term of patent 14 years

Int. Cl. D9—02

U.S. Cl. D9—290

Fig. 4

Fig. 3

Fig. 5

Fig. 2

Fig. 1

FIG. 1 is a perspective view of a combined pour spout and hanger for a container showing my new design;

FIG. 2 is a side elevational view on a reduced scale showing a modified form of my new design;

FIG. 3 is a side elevational view on a reduced scale of the form shown in FIG. 1;

FIG. 4 is a top plan view of the form seen in FIG. 2; and

FIG. 5 is a top plan view of the form seen in FIG. 3.

I claim:

The ornamental design for a combined pour spout and hanger for a container, as shown and described.
